PRESSURE APPLYING PAD

Sidney J. Finn, Beverly, Mass., assignor to United Shoe Machinery Corporation, Paterson, N. J., a corporation of New Jersey

Application July 19, 1934, Serial No. 735,920

16 Claims. (Cl. 12—38)

This invention relates to improvements in pads for use in applying pressure to shoe bottoms and is illustrated herein as embodied in a pad particularly adapted for use in cement attaching soles to shoes.

Most of the machines in use today for cement attaching soles to shoes utilize some form of pad for pressing the sole against the shoe bottom. Many of these pads comprise hollow vessels or bags containing fluid, for example air or water, and provided with flexible sole-engaging walls which conform substantially to the longitudinal contour of a shoe bottom, the outer surfaces of these walls being distorted by the sole and shoe when the latter are pressed against the pad. The sole-engaging walls of pads of the types referred to are usually composed of a composition of rubber and their flexibility is practically the same throughout their entire areas since the walls are supported against the pressure of the sole and shoe only by air or water. While this uniform flexibility is satisfactory for some types of shoes it is not so desirable when operating, for example, upon a shoe in which the outsole at the forepart is to be relatively flat while the sole margins at the shank portion are to be wrapped closely about the upper to produce a close fitting shank. Under such circumstances it is advantageous to have the flexibility of the sole-engaging wall vary somewhat at different portions of the pad in order to apply only a limited pressure to those parts of the shoe bottom which it is desired to maintain in a flat condition while applying a substantially greater pressure to portions which are to be wrapped closely about the shoe upper. Such a construction prevents, for example, excessive rounding of the sole margins at the forepart and heel portions of the shoe and yet permits the margins at the shank to be rolled or wrapped about the shoe upper as much as may be required to produce a close fitting shank.

When a sole and shoe are pressed against a yielding surface such as the sole-engaging wall of a flexible pad there is a tendency for the shoe to tilt or roll sidewise toward the inside of the shoe on account of the greater bottom area of the shoe at the outside of the forepart. It will be seen that if the flexibility of the sole-engaging wall is substantially the same throughout its entire area this condition cannot be overcome without the aid of means independent of the pad itself for holding the shoe upright as it is pressed into the yielding surface of the pad.

It is an object of the present invention to provide an improved pad of such a character that ob-

jectionable wrapping of the sole margins about the shoe upper at the forepart and heel portions of the shoe will be eliminated without reducing the desired wrapping effect at its shank portion. A further object is the provision of a pad which will prevent tilting or rolling of the shoe and sole sidewise during the sole-pressing operation.

To the attainment of these objects there is provided, as herein illustrated, a pressure-applying pad having a cellular forepart filled with relatively fluent material such as sand adapted to lock or become set under pressure, and a fluid-filled shank portion, the heel portion of the pad being solid and relatively inflexible. This heel portion is preferably composed of solid relatively resilient material such as rubber composition which is relatively hard and inflexible and which will not be displaced or distorted any substantial amount by a sole and shoe under sole-attaching pressure. The cellular forepart and the solid heel portion of the pad cannot be distorted any great amount even under considerable pressure. Consequently there will be practically no bulging of the sole-engaging wall of the pad adjacent to the sole margins at these portions of the shoe and therefore no wrapping of the margins about the upper at such portions. The fluid-filled shank portion, on the other hand, is relatively flexible and will bulge sufficiently under pressure to wrap the sole margins closely against the upper at the shank portion of the shoe. Moreover, the substantially rigid and inflexible character of the heel portion of the pad prevents the sole and shoe from tilting or rolling toward the inside of the shoe as they are sunk into the more flexible portions of the pad by the so-attaching pressure, this inflexible portion cooperating with the pressure-applying means to clamp the shoe upright and thus prevent it from tipping sidewise under the pressure applied to the unbalanced areas at the forepart of the shoe.

With the above and other objects and features in view the invention will now be described in connection with the accompanying drawing and thereafter pointed out in the claims.

In the drawing,

Fig. 1 is a longitudinal sectional view of a pad embodying the present invention, the pad being mounted on a supporting structure;

Fig. 2 is a plan view of the pad shown in Fig. 1 with portions of the sole-engaging wall broken away;

Fig. 3 is a transverse sectional view taken on the line III—III of Fig 2;

Fig. 4 is a top plan view of the water bag utilized

in the shank portion of the pad, the bag having a portion of its upper wall broken away;

Fig. 5 is a side elevation of the water bag with portions broken away; and

5 Fig. 6 is a detail view on an enlarged scale and partly in section illustrating the manner in which the seal in the water bag is secured therein.

The illustrated sand and water pad of the present invention was developed for use in a machine 10 of the type disclosed in an application for Letters Patent of the United States, Serial No. 636,202, filed on October 4, 1932, in the name of Milton H. Ballard et al. The pad as herein illustrated is mounted on a supporting structure of the character disclosed in Letters Patent of the United 15 States, No. 2,017,982, granted October 22, 1935, on an application filed in the name of Frank R. Merritt, this structure comprising a box-like frame in which is mounted a solid pad 10 of relatively firm material such as tough and resilient 20 but by no means rigid rubber. The upper surface of the solid pad 10 slants upwardly toward each end so that it will conform more closely to the longitudinal contour of a shoe bottom. Resting 25 on the upper surface of the pad 10 is the combination sand and liquid pad 12, preferably of rubber, which embodies the subject matter of the present invention and which will now be described in detail. The forepart of the pad 12, as 30 disclosed in the Ballard et al. application mentioned above, is of cellular construction with cells or compartments 14 extending from the toe end of the pad rearwardly substantially to the break or ball line. As shown in the application referred 35 to the pad is provided with sixteen cells having a capacity of about one cubic inch although the number and size of the cells could be varied if desired to suit different conditions. The cells 14 are separated by thin rubber walls 16 and, with 40 the exception of the two cells at the opposite sides of the toe end of the pad, are substantially cubical in shape, as shown in Fig. 2, the resilient walls 16 merging into an upper wall 15 and a lower wall 17 of the pad. The cells are filled as completely 45 as possible with a relatively fluent material 18 such as sand or some other finely divided solid material of such a character that, while not having all the pressure transmitting characteristics of liquid, will nevertheless flow to a considerable 50 extent when not under pressure. After the sand is introduced into the cells the latter are hermetically sealed so that the sand cannot escape regardless of the pressure applied to the pad.

A sand well suited for the present purpose is 55 disclosed in Letters Patent of the United States, No. 2,012,272, granted Aug. 27, 1935, upon my application; this is natural windblown sand the grains of which run from about .02 to about .04 of an inch in diameter. These grains are substantially spherical in shape and appear when magnified to be ground rather than polished. As 60 pointed out in the patent just mentioned, sand of this character will flow and rearrange itself freely when not under pressure but when substantial pressure is applied will become stabilized or "locked" to form a substantially rigid mass. Since the amount of initial pressure upon the pad necessary to cause its sole-engaging surface to conform to the contour of a shoe bottom and to 65 set up a stabilized condition in the sand is relatively slight, the sand will become set before sufficient pressure has been applied to cause the shoe and sole to sink any substantial distance into the sole-engaging surface of the pad. The sand outside the periphery of the sole, not receiving any

substantial pressure, is still free to flow and arrange itself without distorting the upper surface of the pad. There will be no tendency, therefore, for the portions of the sole-engaging surface adjacent to or outside the edge of the sole to bulge and thus wrap the sole margins about the shoe upper. After the pressure on the pad is released the stabilized condition of the sand is disturbed by the resilient walls 16, which have been distorted under the sole-attaching pressure, 10 and the sand is returned by these walls to its original loose condition.

As disclosed in the Ballard et al. application referred to above, in order to permit the pad to wrap the sole margins into close fitting relation 15 to the upper at the shank portion of the shoe this portion of the pad has a hollow or cavity 20 formed therein which is shaped to receive a fluid-filled bag 22, the bag fitting snugly into the cavity and having an upper wall 23 which conforms substantially to the shape of the sole-engaging wall 15 of the pad. The bag 22 is filled with liquid such as water 24 and is sealed by a cylindrical plug 26, which, as shown in Fig. 6, is vulcanized into the rubber material of the lower wall of the bag. 25 The plug or seal 26 has two peripheral flanges 28 and 30 projecting therefrom and these flanges are provided with a plurality of countersunk holes 32 into which the rubber of the bag flows when the seal is being vulcanized thereto, thus 30 insuring that the seal will be permanently secured to the bag. It will be noted in Fig. 6 that a thin layer 33 of rubber extends across the inner side of the seal, this layer being provided with a hole 34 through which fluid is introduced into 35 the bag. The hole 34 is plugged with a screw 36 which is threaded into a central opening in the member 26, the screw bearing upon a fiber washer 38 to make the construction water-tight.

The upper wall 23 of the bag 22, as shown in 40 Figs. 4 and 5, is provided with a groove 40 which is arranged to receive a ridge or rib 42 (Fig. 3) projecting downwardly from the inner surface of the sole-engaging wall of the pad, the rib extending longitudinally of the shank portion of 45 the pad substantially along its median line. The rib 42 may be about $\frac{1}{8}$ of an inch thick and approximately an inch in width and serves to strengthen the pad and increase its flexibility at the shank portion.

The rear or heel portion of the pad 12, as shown in Fig. 1, is formed of solid material, part of which is rubber of the same character as that forming the forepart and shank portions of the pad and the remainder of which comprises a relatively rigid mass 44 of rubber composition vulcanized to the relatively flexible rubber referred to. The rubber composition 44 extends across the pad for the greater portion of its width, as shown in dotted lines in Fig. 2, and at its upper 60 side is covered by the flexible rubber forming the sole-engaging wall of the pad. This rubber composition may be formed by grinding fabric material, which has been impregnated or "frictionized" on both sides with rubber, into small pieces 65 and then vulcanizing this ground material into a substantially rigid mass. After it has been vulcanized the material is hard enough to withstand a substantial amount of pressure without being compressed or distorted any considerable amount. This material is then vulcanized to the flexible rubber at the heel end of the pad 12 as shown in Figs. 1 and 2 and renders this portion practically inflexible except for the relatively thin 75

covering formed by the softer rubber of the sole-engaging wall 15.

It will be seen from what has been described that the pad is so constructed as to prevent the sole-engaging wall 15 from wrapping the sole margins about the shoe upper at the forepart and at the heel seat portion of the shoe while permitting such action to take place at the shank portion. The relatively rigid heel portion of the pad also acts to prevent tilting or rolling of the sole and shoe sidewise during the application of pressure thereto since it cooperates with the pressure-applying means to form a clamp for holding the shoe upright as it sinks into the more flexible portions of the pad. Consequently, regardless of the greater area of the shoe bottom at the outside of the forepart the pressure thereon cannot tip the shoe sidewise because of the clamped condition of its heel portion.

20 The sole-engaging wall 15 is reinforced near but, as illustrated, not at its outer surface with a layer of fabric material such as canvas 46, this layer extending over the entire area of the sole-engaging wall. A second layer of canvas 48 is molded into the forepart of the pad a short distance below the layer 46 and extends rearwardly substantially to the tip line of a shoe, indicated at A in Fig. 1, mounted in operative position on the pad. The layer 48 gives additional reinforcement to the forepart of the pad which is subjected to a considerable strain during the sole-attaching operation. These layers of canvas are first impregnated with rubber and are then vulcanized into the sole-engaging wall, each layer 35 being positioned so that the warp threads extend lengthwise of the pad and the woof threads widthwise.

The rib 42, which is formed in the shank portion of the pad, permits the upper wall of the pad 40 to stretch a limited amount at this portion so that it will wrap the sole margins tightly about the shoe upper. In order to prevent the pad from blowing out at the sides and at those portions not engaged by the shoe bottom, the inside of the pad 45 is reinforced at the shank portion with separate layers 50, 52 of fabric material such as canvas which extend from the lower edges of the side walls at each side of the pad and cover the inner surfaces of these walls and the inner surface of 50 the sole-engaging wall, both layers terminating at the outer edges of the rib 42, thereby leaving the lower surface of the rib without a canvas covering. These inner layers 50, 52 of reinforcing material are impregnated on one side with 55 rubber to facilitate their attachment by vulcanization to the inner walls of the pad. While the layer of canvas 46 is vulcanized into the sole-attaching wall during the molding of the pad, the inner layers are pressed into the cavity 20 after 60 the pad has been molded and semi-cured so that there is no substantial stretching or weakening of the canvas as it is being vulcanized to the inner walls of the pad. Since the canvas on the inside of the pad does not extend across its entire width but is separated by the rib 42, it will 65 be seen that the shank portion of the pad can stretch somewhat when pressure is applied to the sole and shoe, this stretching action being limited only by the canvas layer 46 which, however, 70 does allow a certain amount of stretching to take place.

In order that the shoe and sole will rest more evenly on the pad before the sole-attaching pressure is applied, the outer side of the forepart of the sole-engaging wall 15 is built up slightly to

form a raised portion 54, this construction being substantially the same as that disclosed in the Ballard et al. application referred to above. By supporting the shoe in a substantially upright position before pressure is applied, the raised 5 portion 54 cooperates with the solid heel portion 44, which tends to keep the shoe from tilting widthwise on the pad, and thus causes the sole and shoe to be positioned upright as they sink into the sole-engaging surface of the pad. The 10 pad shown in Fig. 2 is adapted for operating upon a right shoe and shows the raised portion at the upper side of the forepart of the pad. A pad for a left shoe would of course show the raised portion located at the opposite side of the forepart. 15

Having described my invention, what I claim as new and desire to secure by Letters Patent of the United States is:

1. A pad for use in applying pressure to shoe bottoms comprising a container having sand in 20 its forepart and fluid in its shank portion, the heel portion of said container being composed of solid material.

2. A pad for use in applying pressure to shoe bottoms comprising a container having a cellular 25 forepart filled with sand, a hollow shank portion filled with liquid, and a solid and relatively inflexible heel portion.

3. A rubber pad for use in applying pressure to shoe bottoms having a cellular forepart filled 30 with sand, a hollow shank portion filled with fluid, and a solid rubber heel portion.

4. A pad for use in applying pressure to shoe bottoms comprising a flexible member having a cellular forepart filled with sand, a hollow shank 35 portion filled with fluid, a solid heel portion of less flexibility than the rest of the pad, and a solid but somewhat yielding member for supporting said flexible member.

5. A pad for use in applying pressure to shoe 40 bottoms comprising a rubber member having a cellular forepart filled with sand, a hollow shank portion, a fluid-filled bag in said shank portion, and a solid rubber heel portion which is less flexible than said forepart and shank portions. 45

6. A pad for use in applying pressure to shoe bottoms comprising a box, a cellular container in the box having sand in its forepart and a fluid-filled bag under its shank portion, the heel portion of said container being composed of solid 50 material which is relatively inflexible, and a resilient member in the box for supporting said container.

7. A pad for use in applying pressure to shoe bottoms comprising a rubber container provided 55 with a sole-engaging wall supported at the forepart by sand, at the shank portion by fluid and at the heel portion by rubber, the heel portion of said container being relatively inflexible so that a sole and shoe operatively positioned on said 60 wall will be prevented from tilting about a longitudinal axis when pressure is applied to the shoe.

8. A pad for use in applying pressure to shoe bottoms comprising a cellular member the forepart of which is filled with sand, said member 65 having a hollow shank portion supported by a fluid-filled bag, the heel portion of said member being composed of relatively hard rubber overlaid with softer rubber for engaging the sole.

9. A pad for use in applying pressure to shoe 70 bottoms comprising a container having a flexible wall for engaging the sole of a shoe to which pressure is to be applied, a plurality of cells filled with sand underlying the forepart of said wall, a fluid-filled bag underlying the shank por- 75

tion of said wall, and substantially rigid material underlying the heel portion of said wall and rendering said heel portion relatively inflexible, thereby preventing tilting of the sole and shoe about a longitudinal axis when pressure is applied to the shoe.

10. A pad for use in applying pressure to shoe bottoms having a sole-engaging wall and side walls of flexible material, said sole-engaging wall having a rib projecting downwardly from its inner face along the median line of the pad, the inner surface of said wall and each side of the rib being covered with fabric material which also covers the inner surfaces of the side walls, thereby reinforcing said walls while leaving the lower surface of the rib unreinforced so that the material thereof can stretch during the application of pressure to a sole and shoe.

11. A pad for use in applying pressure to shoe bottoms comprising a cellular member having sand in its forepart, fluid in its shank portion, and a solid and relatively inflexible heel portion, said member having a sole-engaging wall for receiving the sole of a shoe to which pressure is to be applied, said wall being shaped to conform substantially to the longitudinal contour of a shoe bottom and being reinforced adjacent to its outer surface with fabric material, said wall being also reinforced at its shank portion with fabric secured to its inner surface.

12. A pad for use in applying pressure to shoe bottoms comprising a container having a relatively flexible forepart filled with sand, a liquid-filled shank portion, and a solid heel portion which is less flexible than said forepart and said shank portion, said container having a sole-engaging wall and side walls of rubber, said sole-engaging wall being reinforced adjacent to its outer surface with fabric material extending over the entire area of said wall and being reinforced at its shank portion with fabric material vulcanized to the inner surface of said portion, said fabric material also extending over the inner and lower surfaces of the side walls and reinforcing said walls.

13. A pad for use in applying pressure to shoe bottoms having a sole-engaging wall and side walls of rubber, said sole-engaging wall being provided with a downwardly projecting rib extending along the longitudinal median line of the shank portion of the pad, and the inner sur-

face of said wall being reinforced at said shank portion with fabric material which covers the opposite sides of the rib but does not cover its lower surface, said fabric material also covering the inner surfaces of said side walls, thereby reinforcing the shank portion of the pad except in the region of the rib, stretching of which is thus permitted.

14. A pad for use in applying pressure to shoe bottoms comprising a relatively yielding member having a sole-engaging surface supported at the forepart by sand, at the shank by fluid, and at the heel portion by solid material, said surface having a raised portion at the outside of its forepart arranged to engage the forepart of a sole operatively positioned thereon, and thereby to assist in maintaining the sole and shoe in an upright position as they are sunk into the sole-engaging surface of the pad by the sole-attaching pressure.

15. A pad for use in applying pressure to shoe bottoms comprising a relatively yielding member having a cellular forepart filled with sand, a hollow shank portion filled with fluid, and a solid and relatively inflexible heel portion, said member having a sole-engaging surface with a raised portion at its forepart arranged to engage the outer side of the forepart of a sole mounted thereon so that the sole and shoe will be positioned upright on the pad when pressure is applied to the shoe.

16. A pad for use in applying pressure to shoe bottoms having, in combination, a continuous sole-engaging wall of relatively flexible material supported forwardly of the break line of a shoe mounted thereon by relatively fluent material adapted to become set under pressure and thus to prevent the wall from flexing beyond a limited amount under such pressure, said wall being supported from the break line to the heel breast line of the shoe by material which is readily displaceable under pressure, thereby permitting the entire shank portion of the sole-engaging wall to conform to the curvature of the shank portion of the shoe bottom, and said wall being supported rearwardly of the heel breast line by material which is relatively inflexible under pressure so that the margins of the sole will not be wrapped around the shoe bottom at the heel portion of the shoe.
